UNITED STATES PATENT OFFICE.

MICHAEL FRIEDMAN, OF OTTAWA, ONTARIO, CANADA.

DESIGN FOR A SMOKER'S ASH TRAY.

Application filed March 8, 1922. Serial No. 1,085. Term of patent 3½ years.

To all whom it may concern:

Be it known that I, MICHAEL FRIEDMAN, a subject of the King of Great Britain, and resident of the city of Ottawa, in the Province of Ontario, and Dominion of Canada, have invented a new, original, and ornamental Design for a Smoker's Ash Tray, of which the following is a specification, reference being had to the accompanying drawing, forming part thereof.

Figure 1 is a top plan view of an ash tray showing my new design.

Figure 2 is a front elevation of the same.

I claim:

The ornamental design for a smoker's ash tray as shown.

MICHAEL FRIEDMAN.
